(57) **CLAIM**

The ornamental design for a portion of a wall of an escalator, moving walkway, elevator, or lifting apparatus, as shown and described.

DESCRIPTION

The file of this patent contains at least one drawing executed in color. Copies of this patent with color drawings will be provided by the Office upon request and payment of the necessary fee.

The drawing FIGURE is a front view of a portion of a wall of an escalator, moving walkway, elevator, or lifting apparatus. The claimed design includes shades of blue.

The broken lines surrounding the portion of a wall of an escalator, moving walkway, elevator, or lifting apparatus represent unclaimed environmental structure and the boundaries of the claim and form no part thereof.

The portion of a wall of an escalator, moving walkway, elevator, or lifting apparatus is flat and planar.
